D11-150.

OR D12,082

EX

Design No. 12,082, dated January 4, 1881.

UNITED STATES PATENT OFFICE.

CHARLES DOWLER, OF PROVIDENCE, RHODE ISLAND.

DESIGN FOR A FLOWER-VASE AND SAUCER.

SPECIFICATION forming part of Design No. 12,082, dated January 4, 1881.

Application filed November 12, 1880. Term of patent 3½ years.

To all whom it may concern:

Be it known that I, CHARLES DOWLER, of Providence, in the county of Providence and State of Rhode Island, have invented and produced a new and original Design for Flower-Vases with Saucers, of which the following is a full, clear, and exact description, reference being had to the accompanying photographic illustration, making part of this specification.

10 My invention consists in a design, to be made in terra-cotta, for flower-vases, and used as an ornament for tables, hanging brackets, &c.

15 In the photograph, *a* represents the shell of the vase, which forms the receptacle for holding plants, &c., having its lower portion enlarged. The shell or body of the vase has a plain bead-band, *b*, around its top edge, followed below by the six series of tulip-flowers 20 *c*, alternating with the conventional foliate shell *d*, six in number, which, in turn, are partially overlaid by the leaves *e*. Near the center of the vase is raised the plain and scalloped band *f g*, which serves as a finish for the 25 shell-patterns *d*. The lower portion of the vase is ornamented by reeds *h*, which are par-

tially covered by the six leaves *i*. Near the center, and opposite each other, are fixed the two medallions *k*. The vase rests upon the circular ornamental saucer *l*, supported by 30 four feet, *m*, its border being ornamented by four series of scales, *n*, covered by a leaf, consisting of five each, and connected by a cord. The feet *m* are ornamented by the acanthus-leaf, terminating in a roll-scroll. 35

When used as a hanging vase I substitute the ornamental saucer *o*.

Suitable colors or gilding may be employed to produce a more striking effect.

What I claim as my invention is— 40

A design for a flower-vase with saucer, in which the ornamentation consists of the band *b*, tulip-flowers *c*, shell-pattern *d*, leaves *e*, bands *f g*, reeds *h*, leaves *i*, and medallions *k*, the saucer ornamented by the scales *n* and 45 feet *m*, the whole arranged substantially as herein shown and described.

CHARLES DOWLER.
